UNITED STATES PATENT OFFICE.

CHARLES C. WIENTGE, OF PROVIDENCE, RHODE ISLAND.

DESIGN FOR A BOWL.

SPECIFICATION forming part of Design No. 22,752, dated August 29, 1893.

Application filed July 28, 1893. Serial No. 481,772. Term of patent 7 years.

To all whom it may concern:

Be it known that I, CHARLES C. WIENTGE, of the city of Providence, in the county of Providence and State of Rhode Island, have invented and produced a new and original Design for the Bowls of Tea-Sets; and I hereby declare that the following is a full, clear, and exact description of the same, reference being had to the accompanying drawings, forming part of this specification.

My design consists in the peculiar and novel shape and ornamentation of the bowl and its supports, which together form the most important part of the several articles usually associated together to form a tea-set. In these articles I preserve the usual conventional form by which they are distinguished from each other, as the coffee-pot, tea-pot, water-pot, the creamer, sugar-bowl, and the slop-bowl, and give to the bowl the peculiar and novel shape and ornamentation which characterizes the pieces of which the tea-set is composed.

Figure 1 of the drawings is a perspective view of my new design for bowls, the top, handle and spout of a tea-pot being indicated in dotted lines. Fig. 2 represents a plan view of a bowl representing my new design to illustrate the ornamentation of the upper edge.

The leading features of my new design con-

sist in the vertical flutings with their upper and lower bulbous enlargements which divide the surface of the bowl into eight parts, the concavities between the flutings, the outwardly-turned upper edge, together with the 35 feet and the ornamentation connecting the feet.

The bowl 3 in the drawings is of larger diameter at the bottom than at the top and its surface is divided by eight vertical flutings 40 or panels 4—4 separated by concavities. The upper and lower ends of the flutings are slightly enlarged in bulbous shape. The bowl is supported on feet formed of scrolled ornaments 5—5 connected by other scrolls 6—6 45 with the bowl. Between the ends of the scrolls 6—6 are pendent shell-like ornaments 7—7. The upper portion of the bowl is contracted and then expands to form the lip 8 having a scrolled edge and ornamented on its 50 surface by the raised scrolls 9—9.

What I claim is—

The design for a bowl as herein shown and described.

In witness whereof I have hereunto set my 55 hand.

CHARLES C. WIENTGE.
